(57) **CLAIM**

The ornamental design for an evaporator air cooler, as shown and described.

DESCRIPTION

FIG. 1 is a perspective view showing the new design of an evaporator air cooler.

FIG. 2 is a front side view thereof.

FIG. 3 is a left side view thereof.

FIG. 4 is a right side view thereof.

FIG. 5 is a back view thereof.

FIG. 6 is a top view thereof; and,

FIG. 7 is a bottom view thereof.

The broken lines in the drawings illustrate portions of the evaporator air cooler and form no part of the claimed design.
